UNITED STATES PATENT OFFICE.

GERRIT VYNE, OF NORTH WILKESBOROUGH, NORTH CAROLINA.

NUT-LOCK.

SPECIFICATION forming part of Letters Patent No. 536,711, dated April 2, 1895.

Application filed February 7, 1895. Serial No. 537,638. (No model.)

To all whom it may concern:

Be it known that I, GERRIT VYNE, a citizen of the United States, residing at North Wilkesborough, in the county of Wilkes and 5 State of North Carolina, have invented a new and useful Nut-Lock, of which the following is a specification.

The invention relates to improvements in nut locks.

10 The object of the present invention is to improve the construction of nut locks, and to provide a simple and inexpensive one adapted to be employed on rail-joints, switches, frogs, and locomotive engines and the like, and 15 capable of securely locking one or more nuts against accidental unscrewing.

Another object of the invention is to enable the nuts to be removed when desired, without impairing the future usefulness of the nut 20 lock.

Furthermore, it is the object of the invention to provide a nut lock which will require no change in the construction of the bolts or nuts usually employed.

25 The invention consists in the construction and novel combination and arrangement of parts hereinafter fully described, illustrated in the accompanying drawings, and pointed out in the claims hereto appended.

30 In the drawings: Figure 1 is a perspective view of a nut lock constructed in accordance with this invention. Fig. 2 is a horizontal sectional view of the same. Fig. 3 is a vertical sectional view. Fig. 4 is a longitudinal 35 sectional view of the nut lock, illustrating the manner of locking a single nut.

Like numerals of reference indicate like parts in all the figures of the drawings.

1 designates a plate, which may be a fish- 40 plate, and it is provided with bolt-openings and is disposed horizontally on bolts 2, of a rail-joint. The plate 1 is provided at its upper and lower edges with opposite longitudinal grooves 3, forming upper and lower ribs, 45 4, substantially T-shaped in cross-section and adapted to engage corresponding grooves 5, of a metal box 6, adapted to receive and prevent the rotation of nuts 7.

The box is substantially rectangular in 50 cross-section, and consists of similar sides, which are arranged at the top and bottom of

the nuts, an outer wall or top 8, and an end 9. The other end of the box is open to permit it to be inserted endwise on the plate 1 to cover the nuts, the closed end of the box forming a 55 stop to prevent further movement than is necessary to properly cover the nuts. The box, whose sides prevent the rotation or unscrewing of the nuts, is detachably locked in position by a substantially L-shaped spring 60 10, disposed between the nuts of a pair of bolts and provided at one end with an opening receiving one of them and having one arm which is short disposed horizontally and extending outward and engaging detachably 65 an opening 11 of the box. The engaging arm 12 of the L-shaped spring is adapted to be depressed by a nail or any tool that will enter the opening 11, to disengage it from the box to enable the latter to be removed from the 70 plate 1.

The nut lock may be applied to any number of nuts, as will readily be seen, and when it is employed for locking a single nut the L-shaped spring is preferably arranged to engage the open end of the box, as illustrated 75 in Fig. 4 of the accompanying drawings.

It will be seen that the nut lock is exceedingly simple and inexpensive in construction, that it is positive and reliable in operation, 80 and that when it is desired to unscrew the nuts for any purpose whatever, the box may be removed without injuring any of the parts. The spring is rigidly secured to one of the bolts by means of a supplemental nut 14, and 85 a corresponding nut may be arranged on the other bolt, if desired.

Changes in the form, proportion, and the minor details of construction may be resorted to without departing from the principle or 90 sacrificing any of the advantages of this invention.

What I claim is—

1. A nut lock comprising a plate having a bolt-opening and adapted to receive a bolt, 95 an L-shaped spring rigidly secured to the bolt and having one of its arms extending outward, and a rectangular box slidably arranged on the plate and adapted to cover a nut and to engage the sides of the same to 100 prevent accidental unscrewing, said box being detachably engaged by the outward-ex-

tending arm of the spring, substantially as described.

2. The combination with bolts, nuts arranged thereon, a plate having bolt-openings 5 and arranged on the bolts and provided at its longitudinal edges with ribs, a rectangular box having one end closed and provided at opposite sides with ways adapted to receive the said ribs, whereby the box is slidingly 10 mounted on the plate, said box being provided with an opening, and an L-shaped spring rig-

idly secured to one of the bolts and having one of its arms extending outward and engaging the opening of the box, substantially as described.

In testimony that I claim the foregoing as my own I have hereto affixed my signature in the presence of two witnesses.

GERRIT VYNE.
